UNITED STATES PATENT OFFICE

ALBERT ERWIN BURDETT AND JOSEPH PATRICK GILLIGAN, OF ALAMEDA, CALIFORNIA

GRAIN SEPARATOR

Application filed May 13, 1929. Serial No. 362,662.

The present invention relates to a grain separator and has for its prime object to provide in combination improved conveyor means, sieve means and air deflectors.

Another very important object of the invention resides in the provision of an apparatus of this nature which is comparatively simple in its construction, strong and durable, compact and convenient in its arrangement of parts, adjustable, and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

In the drawing:

Figure 1 is a top plan view of the apparatus embodying the features of my invention,

Figure 2 is a side elevation thereof,

Figure 3 is a vertical longitudinal section therethrough,

Figure 4 is a vertical transverse section taken substantially on the line 4—4 of Figure 3,

Figure 5 is a detail section taken substantially on the line 5—5 of Figure 3, and

Figure 6 is a perspective view showing one of the connecting plates of the conveyor.

Referring to the drawings in detail it will be seen that numerals 5 denote a pair of horizontal spaced parallel coextensive panel beams supported on uprights 6 and having bearings 7 at their ends in which are journaled shafts 8 and 9.

A roller 10 is mounted on the shaft 8 and a roller 11 is mounted on the shaft 9, said roller 11 being provided with cutaway intermediate portions one adjacent each end to form cams 12. A platform 14 is disposed between the beams 5 extending from approximately the center thereof to the ends adjacent roller 10.

An endless conveyor is trained over the rollers 10 and 11 and comprises two series of end plates and a single series of center plates

15. The end and center plates are connected by link rods 16 and the plates of the three series are connected by links 17.

A sieve 20 is mounted on angle irons 21 and a sieve 22 is mounted on angle irons 23. The angle irons 23 are mounted between the angle irons 21 and the sieve 22 is located below the sieve 20. The angle irons 23 are provided with longitudinal slots 24. Bolts 25 extend through longitudinal slots 26 in the beams 5, through openings in the angle iron 22 and through the slots 24 in the angle irons 23.

A pair of links 27, 28 are associated with angle irons 23 and 21 at each side of the apparatus. The link 27 is pivotally engaged with angle iron 23 as at 29, pivotally engaged with link 28 as at 30 and the link 28 is pivotally engaged with angle irons 21 as at 31.

The pivot 31 is in the form of a bolt and is accessible through a slot 32 in the adjacent beam 5. Thus by loosening the bolts 31 and changing the angles of the links 27 and 28 in respect to each other the sieves may be adjusted with respect to each other to control the size of the particles which may pass therethrough.

Inverted members straddle the cams 12 and have rods 33 extending therefrom and adjustably connected as at 34 with angle irons 23.

A pan or casing depends from the beams 5 having an inclined bottom 35 directed upwardly toward the roller 11 and at the bottom end of the bottom 35 there is a collection receptacle 36 for the grain. A fan casing 38 communicates with the casing C through an opening 39 and has fan means 40 therein for blowing a draft of air through said opening 39.

Crank 41 are pivotally mounted in the side walls of the opening 39 and held in adjusted position by means of nuts 42. On the inner ends of these cranks are deflectors or baffle plates 43. Obviously the cranks 41 may be adjusted to relative positions of the plates 43 in respect to each other and control the current of air from the fan to the casing C.

A casing 44 is mounted at one end of the apparatus over the roller 11 and extends below said roller, the bottom end forming a

collection trough 45. A pulley 46 is mounted on one end of the shaft 8 and a pulley 47 is mounted on the outer end of the shaft 48 of the fan 40.

5 When these pulleys are rotated in any preferred manner and grain is dropped on the plate or platform 14 it will be seen that the endless conveyor will move this grain over on the sieves permitting the grain to fall 10 through the sieves into the casing C and the good grain will collect in the receptacle 36 while the chaff or the like will be blown into the casing 44 and collect in the trough 45.

15 It is thought that the construction, operation, utility and advantages of this invention will now be quite apparent to those skilled in this art without a detailed description thereof.

20 The present embodiment of the invention has been disclosed in considerable detail, merely for the purposes of exemplification since in actual practice it attains the features enumerated as desirable in the statement of the invention and the above description.

25 It will be apparent that changes in the details of construction, and in the combination and arrangement of parts may be resorted to without departing from the spirit 30 or scope of the invention as hereinafter claimed or sacrificing any of its advantages.

Having thus described our invention, what we claim as new is:

35 A grain separator, a supporting frame including side members respectively provided at spaced points with slots elongated in the longitudinal direction of the members, a pair of relatively long and short mesh screens of channel shaped cross section extending longitudinally between the slotted portions of the side members and nesting one within the other, cross rods carried by the outer screens and engaging the inner screen to support the same, said rods being slidably supported 40 in corresponding slots of the said side members, a rotatable cross bolt carried by said outer screen and having threaded ends exposed through other corresponding slots in the said side members, a pair of pivotally connected links coupling the said bolts with the inner screen, one of said links being pivotally connected with the inner screen and the other link being rigidly connected with the said bolt, clamping means on the 45 threaded ends of said bolts for holding the same against rotation relative to the said outer screen and being accessible through the said other corresponding slots for operation to release the bolts for relatively adjusting the said screens and means for reciprocating said screens.

50 In testimony whereof, we affix our signatures.

ALBERT ERWIN BURDETT.

65 JOSEPH PATRICK GILLIGAN.
